UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

MACHINE FOR APPLYING METALLIC FASTENERS TO ENVELOPS.

965,252.

Specification of Letters Patent. Patented July 26, 1910.

Application filed October 25, 1906. Serial No. 340,495.

To all whom it may concern:

Be it known that I, WILLARD E. SWIFT, a citizen of the United States, residing in Worcester, in the county of Worcester and 5 Commonwealth of Massachusetts, have invented a new and useful Improvement in Machines for Applying Metallic Fasteners to Envelops, of which the following is a specification accompanied by drawings forming 10 a part of the same.

The object of my present invention is to provide a machine for automatically attaching a metal fastener to the body of an envelop, and it comprises the combination 15 in a single machine of means for selecting a fastener from a mass of fasteners and presenting it individually in proper position to be attached to the body of the envelop; means for suitably registering the envelop; 20 means for attaching the fastener to the body of the envelop, and means for simultaneously punching and staying a hole in the seal flap in proper position to receive the metal fastener when the envelop is closed.

25 Figure 1 is a side view of a machine for applying metallic fasteners to envelops, and embodying my invention. Fig. 2 represents an envelop with a metallic fastener applied thereto. Fig. 3 is a transverse sectional view 30 through the body of the envelop on line 3—3, Fig. 2. Fig. 4 is a perspective view of the metallic fastener before it is attached to the envelop. Fig. 5 is a front view on a larger scale of the upper portion of the 35 machine showing the operative parts that are directly concerned in the selection and application of a metallic fastener to the envelop. Fig. 6 is a front view of the upper part of the machine with portions shown in 40 sectional view. Fig. 7 is a transverse sectional view through the hopper for holding the metallic fasteners, said section being shown on line 7—7, Figs. 5 and 6. Fig. 45 8 is a transverse sectional view through the conveying tube, said section being shown on line 8—8, Figs. 5 and 6. Fig. 9 is a side view of a portion of the machine shown partly in section in order to disclose the 50 operative parts employed in applying the metallic fastener to the body of the envelop. Fig. 10 is a top view of the plunger for pushing the fastener through the body of the envelop. Fig. 11 is a top view of the mechanism for supporting a fastener in regis-

tration with the reciprocating plunger. Fig. 55 12 is an enlarged view of a portion of the conveying tube 10, partly in section, showing the position of the overlapping fasteners as they pass through the tube.

Similar reference letters and figures refer 60 to similar parts in the different views.

In the accompanying drawings, I have shown my invention as embodied in a machine adapted to attach to the body of the envelop a metallic fastener of the form illustrated 65 in perspective view in Fig. 4, although the shape of the fastener may be somewhat varied without departing from the scope of my present invention.

My invention consists in the construction 70 and arrangement of parts as hereinafter described and set forth in the annexed claims.

The metallic fastener A upon which the machine illustrated in the accompanying 75 drawings, is designed to operate, is illustrated in Fig. 4, and it consists of a plate 1 having on opposite sides laterally projecting bendable tongues 2, 2, and provided at its corners with pointed attaching spurs 3, bent 80 at an oblique angle to the plane of plate 1. The fastener A is attached to the body B of an envelop near its open end, as shown in Figs. 2 and 3, and this is accomplished by forcing the spurs 3 through the body of the 85 envelop and clenching them upon the inside of the envelop at 3^a, 3^a, Fig. 3, with the bendable tongues 2, 2, lying transversely upon the outside of the envelop, and in a position to be bent together and entered 90 through a hole 4 formed in the seal flap C, and again extended in order to hold the seal flap against the body of the envelop. In order to strengthen the seal flap it is preferably stayed by the attachment thereto of a 95 patch 5 of cloth or paper.

The operative parts of the machine, by which the fasteners are attached to the body of the envelop, consist of an elevated hopper 7, supported on the free end of a bracket 8. 100 The side 9 of the hopper is inclined so that a fastener resting against the side will slide by gravity toward the open end of a conveying tube 10, through which the fasteners are conducted to the mechanism for attaching them to the body of the envelop. The upper end of the conveying tube 10 is partially closed by a wedge-shape plate 11,

which leaves a restricted entrance 12 to the tube, barely sufficient to allow the plate 1 of the fastener to pass when the fastener is lying upside down against the hole of the hopper in the position shown at A, Fig. 7, and with the spurs 3, 3 pointing upward. The side 9 of the hopper is provided with a groove 13 having inclined side walls 14, and having the bottom of the groove slightly 5 wider than the width of the fastener. The upper end of the plate 11 that determines the entrance to the conveying tube 10 is slightly raised above the bottom 15 of the hopper, and inclosed within the hopper is a 10 rotating brush 16 carried by a shaft 17, and rotating in the direction of the arrow 18. The hopper 7 is partially filled with a mass of fasteners which are agitated by a rotating brush 16 which, at each revolution, 15 sweeps against the upper end of the plate 11, thereby removing any fasteners which may have become lodged at the entrance of the tube 10. During the agitation of the fasteners by the brush 16, those fasteners which 20 chance to fall into the groove 13, and in position shown at A, Fig. 7, are permitted to slide by gravity through the restricted entrance 12 into the conveying tube 10, through which they slide downward until 25 resting by a spring actuated pawl 19 swinging loosely upon a stud 20, and held in its normal position by a spiral spring 21, attached at one end to a fixed portion of the machine, and at its opposite end to a pin 30 22 projecting from the pawl 19. The free end of the pawl 19 is bifurcated, forming two tips 23, 23, the inner corners of which rest against the bar 24, supported in the center of the conveying tube 10, and in position 35 22 to be straddled by the spurs 3 of the fastener, which, in its course from the hopper, has been turned over a half revolution by means of a twisted section 25 on the conveying tube 10. As the fastener moves over 40 the bar 24 in the position shown at A¹, Fig. 6, with the spurs 3 suspended at the sides of the bar 24, its downward motion is checked by its contact with the tips 23, 23 of the pawl 19, thereby arresting the downward 45 movement of all of the fasteners which have already entered the conveying tube 10. The bottom of the conveying tube 10 is provided with an opening 26 opposite the central portion of the bar 24 to permit the rotation of an arm 27 attached to a rotating shaft 28 journaled in ears 29 depending from the conveying tube 10.

The arm 27 is bifurcated, forming tips 30, 30 which, as the arm revolves, straddles 50 the bar 24 and strikes against the rearmost spurs 3 of the foremost fastener, which is then held by its contact with the pawl 19. The rotation of the arm 27 pushing against the foremost fastener crowds it past the 55 pawl 19, which is slightly raised against

the tension of the spring 21, and allows the released fastener to slide over the lower free end 31 of the bar 24 into the delivery tube 32, through which it slides by gravity into its final position beneath the plunger 33, as shown at A², Fig. 6. As the fastener is brought to its final position beneath the plunger 33, it slides over the upper edges of the blades 34, 34, located in the center of the delivery tube 32, shown in top view in 75 Fig. 11. The blades 34 are sufficiently near together to be straddled by the spurs 3, and they are far enough apart to allow one of the bendable tongues 2 to descend between them as the fastener slides off the end of 80 the blades and falls into the position shown at A², Figs. 6 and 11, with the spurs 3 resting upon the slidable plates 35, 35, Fig. 9. As the fastener approaches its final resting place upon the plates 35, 35, the advancing 85 bendable tongue slides against the inclined inner surface 36 of a guide box 37. The insertion of one of the bendable tongues 2 in the guide box 37, and of the other bendable tongue between the blades 34, holds the fastener in proper alignment in one direction with the plunger 33, and the opposing ends of the blades 34 and the guide box 37 brings the fastener into proper registration with the plunger in the other direction. 95

Rigidly supported by the frame work of the machine and immediately below the plates 35, 35, is a pointed horn 38, which is inserted in the open end of the envelop as the latter is applied to the machine. The 100 envelop is presented to the machine with the seal flap C inserted in the open space between the horn 38 and the curved guide plate 39 until the advancing edge of the seal flap is brought against the stop pin 40, 105 which is held in an adjustable bar 41, and extends upward through a slot 42 into the path of the advancing seal flap. The bar 41 is adjusted in and out by means of a rod 43, which is held in any desired position by means of a thumb screw 44, passing through the slotted end of the rod and entering the frame work of the machine. That portion of the body of the envelop which is to receive the fastener passes over the top 110 of the horn 38 and is guided into position by a curved guide plate 45. The registration of the envelop by means of the stop pin 40 brings the end of the body B immediately over the ribs 46, 46, against which the spurs 3 are clenched as they are pushed through the body of the envelop by the descent of the plunger 33. The plunger 33 is carried in a sleeve 47, held in an arm 48, projecting from a vertically sliding gate 49, sliding in 115 ways of the frame work of the machine and intermittently actuated by means of a rocking lever 50 pivoted on a shaft 51, and having its end connected by a link 52 with the end of a lever 53, which is pivoted at its 120 125 end of a lever 53, which is pivoted at its 130

opposite end on a rod 54 held in the framework of the machine, and actuated by a cam 55 carried upon the main shaft 56 of the machine.

- 5 Supported in the arm 48, and on diametrically opposite sides of the plunger 33 are vertically slideable bars 57, provided with studs 58, which rest upon a spanner nut 59, carried upon the sleeve 47. The lower ends 10 of the bars 57 rest, when the plunger 33 is in its highest position against the bell crank arms 61, which are carried upon rocking spindles 62. The lower bell crank arms 15 engage the slideable plates 35 so that as the bars 57 are depressed the bell cranks will be rocked to withdraw the plates 35 from beneath the fastener and allow the fastener to fall upon and rest by its spurs 3 upon the body of the envelop. The continued 20 downward movement of the plunger 33 brings it in contact with the fastener and, forcing the spurs 3 through the body of the envelop, and against the upper surface of the ribs 46, causes the spurs to be clenched beneath the body of the envelop, as shown at 25 3^a. After the bell crank arms 61 have reached the limit of their downward movement, during the continued downward movement of the plunger, while forcing the spurs of the fastener through the envelop, the slideable bars 57 are forced upward 30 against the tension of the spiral springs 64, which are attached at one end to the arm 48, and at the opposite end to pins 65 projecting from the bars 57. As the gate 49 rises the slideable bars 57 are restored to their normal position with their studs 58 resting upon the spanner nut 59, and as the plunger reaches its highest position, as shown in 35 Fig. 9, the plates 35 and their actuated bell cranks are reversed by the tension of a spiral spring 66, which connects the radial arms 67, 67 Fig. 11, projecting from the rocking spindles 62, 62.
- 40 The operative parts of the machine as above described, are mounted in a vertical frame work 68, which is supported upon a table 69 resting upon legs 70. Mounted upon the table 69 is a bracket 71, which supports a roll 72 of continuous staying material 73, which is conducted between feed rolls 74 and 75. The stay strip is preferably gummed on its under side, which is moistened by feed roll 75 running in a reservoir of water 76. By the intermittent action of the feed rolls the stay strip is projected forward through a slot 77 in a plate 78. The lower edge of the slot 77 acts in conjunction with one corner of a cutting blade 79, carried upon the lower end of the gate 49 to sever the stay strip and allow the severed end to be carried down and pressed against the seal flap of the envelop by the lower surface of the cutting blade 79. Prior to the attachment of the stay strip to the

seal flap of the envelop, the seal flap and stay strip are both punctured by means of a punch 80 entering a hole 81 in the die plate 82. The intermittent motion is imparted to the feed rolls by means of a pawl 70 and ratchet mechanism 83, Fig. 1, actuated through a link 84 by a crank 85. Rotary motion is imparted from the main shaft 56 to the crank 85 in the present instance by means of sprocket wheels and a 75 chain belt 86, and rotating shaft 28 and brush shaft 17 by chain belts 87 and 88.

The several parts of the operative mechanism are so timed that while the brush 16 is continuously rotated within the hopper 7, 80 causing the individual fasteners to enter at random into the conveying tube 10, the descending column of fasteners in the tube 10 are held from downward movement by the pawl 19 until they are severally released by 85 the rotation of the arm 27 carried on the shaft 28. The rotation of the arm 27 is timed with the reciprocating motion of the gate 49 and the plunger 33, so that as each fastener is attached to the body of an envelop, the next succeeding fastener will be released by the movement of the arm 27, and fall into position as shown at A², Fig. 6, ready for the next downward movement of 90 the plunger. At each upward movement of 95 the plunger, the envelop with a fastener attached thereto, is removed and a fresh envelop inserted upon the horn 38 by the operator. The intermittent movement of the feed rolls 74 and 75 is timed with the reciprocating movement of the gate 49, so that as the latter rises the continuous stay strip 73 is projected over the body of the envelop in position to be severed, punched and pressed upon the seal flap of the envelop 100 simultaneously with the operation of attaching the fastener to the body of the envelop.

The plunger 33 is capable of a slight sliding movement within the sleeve 47, and is 110 held in its lowest position by the tension of a spiral spring 89, thereby making the plunger capable of a slight yielding movement as pressure is applied to the fastener. The horn 38 is clamped into position by a bar 90 115 and clamping screw 91, allowing the horn to be readily removed by releasing the clamping screw 91. The conveying tube 10 is provided on one side with a central slot 92 which is slightly wider than the bendable 120 tongues 2 of the fasteners in order to allow the tongues 2 to overlap the body portion or plates 1 of the adjacent fasteners. By forming a central slot 92 in one side of the tube 10 coincident with the line of bendable 125 tongues 2, the overlapping of the fasteners in the tube 10 is permitted, and the passage through the tube can be made to more closely fit the body portion of the fasteners without clogging the passage. 130

The entrance of the fasteners into the tube 10 is irregular and accidental, but the feeding of the individual fasteners to the plunger 33 is regular and timed with the reciprocating movement of the plunger. As the fasteners are delivered to the tube 10 from the hopper, they are arrested in their downward movement by the pawl 19, until they are released by the rotating arm 27, which is timed to rotate in correspondence with the reciprocating movement of the plunger 33. The shaft 28, which carries the rotating arm 27, is capable of a longitudinal sliding motion, and is connected with the arm by means of a spline 93. One end of the shaft 28 has a knob 94 for moving the shaft endwise, and the opposite end is connected by a clutch 95, with a rotating shaft 96, which enables the arm 27 to be disconnected from the driving power at will, when, for any reason, it is desired to interrupt the feeding of the fasteners to the plunger 33. The plunger 33 is held in a sleeve 47, which is supported in a slot 97 in the arm 48. The sleeve 47 is clamped in position in the slot 97 by means of a flange 98, a rectangular washer 99 adjustable in ways 100 in the arm 48, and a clamping nut 59. By loosening the nut 59 the sleeve 47 may be adjusted in the arm 48 to bring the plunger 33 into registration with the fastener as it is held upon the plates 35.

The operation of the machine is as follows:—A mass of fasteners is placed in the hopper 7 resting against the bottom 15, from which they are continually being swept by the rotating brush 16 against the inclined side 9. As the fasteners strike against the inclined side 9 they slide by gravity toward the restricted opening 12 of the conveying tube 10, but only those fasteners which have been lodged bottom side up in the groove 13, in the position in Fig. 7, are permitted to enter the restricted opening 12, and pass beneath a wedge-shape plate 11 into the conveying tube 10. As soon as the fastener has passed the restricted opening 12 it possesses complete freedom of movement into the conveying tube 10 owing to the increased size of the passage below the wedge-shape plate 11. The central slot 92 allows the bendable tongues 2 to slide over the plates 1 of the fasteners, thereby bringing the body of the fasteners into close contact, as shown in Fig. 12. As the fasteners move down the tube 10 upon the bar 24, the foremost fastener is caught by the pawl 19, and the movement of the line of fasteners is checked until the foremost fastener is released by the rotating movement of the arm 27 whereupon it slides through the delivery tube 32 and over the blades 34 into the position represented at A², Fig. 6. As the fastener slides over the blades 34 it falls upon the plates 35, and is supported thereon by the spurs 3, with one

of its bendable tongues 2 between the blades 34 and the other of these bendable tongues entering the guide box 37. In this position the fastener is ready to be presented to the envelop, and is supported in registration with the reciprocating plunger 33. The envelop is placed upon the horn 38 until the advancing edge of the seal flap is brought into contact with the stop pin 40. The next descending movement of the gate 49 carries the arm 48 downward, causing the bars 57 to rock the bell cranks and withdraw the plates 35 from beneath the fastener which falls upon the surface of the envelop. The continued downward movement of the gate 49 causes the plunger 33 to force the spurs 3 through the body of the envelop and clench them upon the inside of the envelop by their contact with the ribs 46. Simultaneously with the downward movement of the plunger 33 the stay strip 73, which has been fed forward over the body of the envelop, is severed and attached to the seal flap of the envelop, a hole being punched through the stay strip and seal flap by the downward movement of the punch 80 into a hole 81 of the die plate 82.

I claim,

1. In a machine of the class described, the combination of the following instrumentalities, means for advancing a continuous row of fasteners by an intermittent motion, horizontal ways for receiving a fastener from the end of said continuous row, a horizontal plate below said ways for receiving said fastener from said ways, means for withdrawing said plate by movement in a horizontal plane, said ways arranged to prevent movement of said fastener as said plate is withdrawn, a reciprocating plunger above said fastener, a stationary table below said fastener, and means for reciprocating said plunger as said plate is withdrawn.

2. In a machine of the class described, the combination with a feeding mechanism for advancing a fastener from the end of a continuous row of fasteners, comprising a straight bar, yielding means for holding a fastener in contact with said bar, and a rotatable member for imparting a forward movement to said fastener against the restraining force of said yielding means.

3. In a machine of the class described, the combination with a feeding mechanism for advancing a fastener from the end of a continuous row of fasteners, comprising a support for said fastener, a spring actuated finger acting in co-operation with said support to seize said fastener, and a rotatable member arranged to lift said finger and release said fastener.

4. In a machine of the class described, the combination with a feeding mechanism for advancing a fastener from the end of a continuous row of fasteners, comprising a sup-

- port for said fastener, a spring actuated finger acting in coöperation with said support to seize said fastener, a rotatable member arranged to lift said finger and release said fastener, and means for disconnecting said rotatable member.
5. In a machine of the class described, the combination with means for advancing a continuous row of fasteners by an intermittent motion, horizontal ways for receiving the lowermost fastener in said row and guiding it upon a horizontal support, means for withdrawing said support, means for supporting an envelop below said support, vertical ways above the plane of said support arranged to guide said fastener upon said envelop, means for exerting pressure upon said fastener, and means for returning said support to its original position.
- 10 6. In a machine of the class described, the combination with means for supporting an envelop, a horizontal support for a fastener above said envelop support, a reciprocating plunger, means for withdrawing said fastener support in a horizontal plane as said plunger descends, and means above the plane of said fastener support for preventing lateral movement of said fastener as said support is withdrawn.
- 15 7. In a machine of the class described, the combination with means for imparting a downward motion to a fastener from one end of a continuous row of fasteners a support for a fastener, means for directing said fastener to a predetermined position upon said support, means for horizontally withdrawing said support, and means above the plane of said support for holding said fastener in said position while said support is withdrawn.
- 20 8. In a machine of the class described, the combination with a sliding support for a fastener, a reciprocating plunger above said support, fixed means above the plane of said support and outside the path of said plunger arranged to engage said fastener and hold it from both lateral and longitudinal movement during the descent of the plunger.
- 25 9. In a machine of the class described, the combination with means for attaching a fastener to an envelop, of sliding means for supporting the fastener above the envelop, and fixed means above the plane of said support for determining the position of said fastener on said support, whereby said fastener is held in position during the withdrawal of said support.
- 30 10. In a machine of the class described, the combination with a sliding support for a fastener, of fixed means above the plane of said support for delivering a fastener in a particular position upon said support, whereby said fastener is also retained in said position, said fixed means also serving to
- control the position of said fastener while said support is being withdrawn.
11. In a machine of the class described, the combination of a support for an envelop, a reciprocating plunger for attaching a fastener to the envelop, a pair of slidable plates for supporting the fastener, a pair of bell cranks engaging said plates, and yielding means carried by the plunger for actuating said bell cranks simultaneously with the downward movement of the plunger to withdraw said slidable plates and release the fastener.
12. In a machine of the class described, the combination with an envelop support, a reciprocating plunger, means for supporting a fastener having a horizontal tongue in the path of said plunger, of a guide box having vertical ways above said supporting means to receive said tongue.
13. In a machine of the class described, the combination with an envelop support, a reciprocating plunger and means for supporting a fastener having a horizontal tongue above the envelop support and in the path of the plunger, of a pair of parallel vertical blades above said supporting means arranged to receive said tongue.
14. In a machine of the class described, the combination with an envelop support, a reciprocating plunger, and means for supporting a fastener in a predetermined position above the envelop support, comprising a guide box having an inclined side, and a pair of parallel blades in alinement with said guide box.
15. In a machine of the class described, the combination with means for attaching a fastener to an envelop, of means for supporting the fastener above the envelop, of a guide box to receive one of the bendable tongues of the fastener, said guide box having an inclined upper wall to deflect the tongue of the fastener downward.
16. In a machine of the class described, the combination with a reciprocating plunger and means for advancing a continuous row of fasteners, of a stationary track at one side of the path of said plunger for receiving the lowermost of said fasteners and conducting it beneath said plunger, a movable support for said fastener, means for withdrawing said support, and means upon the other side of the path of said plunger arranged to prevent, together with said track, lateral movement of said fastener as said support is withdrawn.
17. In a machine of the class described, the combination with a conveying tube for conveying a row of fasteners by gravity, a bar inserted in said tube over which the fasteners slide in their downward movement, a pawl with its tip resting on said bar and in the path of said fasteners, a spring for

holding said pawl in its normal position, and a rotating arm whereby the foremost fastener in the row is periodically forced past said pawl.

5 18. In a mechanism of the class described, the combination with a reciprocating plunger for attaching a fastener to an envelop, of a conveyer tube for the fasteners, means for arresting the delivery of a fastener from

said tube, a rotating arm for removing a fastener from said tube, and means for rotating said arm synchronously with the movement of said plunger.

WILLARD E. SWIFT.
